ELECTRIC TIMING MECHANISM

Lloyd Rittenhouse, Honeoye Falls, N. Y., assignor
to The A. E. Rittenhouse Co., Inc., Honeoye
Falls, N. Y., a corporation of New York

Application September 18, 1940, Serial No. 357,304

8 Claims. (Cl. 200—97)

This invention relates to an electric timing mechanism, and has for its object to afford an efficient and practical mechanism, of simple and economical construction, for controlling one or more electrical circuits, through movement of a circuit controlling member, so that several circuits may be closed successively at predetermined intervals, or a single circuit may be closed and opened after a predetermined interval, dependent upon the movement of said circuit controlling member.

Among other applications, the invention has practical utility in the governing of several circuits of a chime signal, where a group of chimes are successively struck by electric striker mechanisms, and it is an object of the invention to afford a structure that is compact and requires little space, one which can be produced at considerably less cost than timing mechanisms such as heretofore used, and which will serve effectively upon the closing of a switch to operate automatically several chimes by closing their striker mechanism circuits at suitable predetermined intervals.

In a more specific aspect, the invention has for its purpose to provide a timing mechanism of improved construction in which a movable circuit controlling member is actuated in one direction by a solenoid, and its return movement to initial position when released is retarded by fluid controlled instrumentalities, during which return movement the several circuits to the respective chime striker mechanisms are successively closed and opened.

Still another object of the invention is to provide an arrangement that permits the successful use of a solenoid plunger which is given a retarded return movement by liquid controlled means by arranging the solenoid in a housing that is completely leak-proof and permanently retains the liquid surrounding the solenoid.

A further purpose of the invention is to afford a durable and reliable mechanism that does not require brackets, rivets, welds, or other such fastening instrumentalities for holding the solenoid in the housing, the solenoid being retained by parts which frictionally engage the housing and which also serve with the housing to complete the magnetic circuit of the solenoid.

An additional purpose of the invention is to provide a structure that requires no fine machining or close fitting parts, is not likely to require servicing, and which can be used to practical advantage wherever there is necessity for exerting predetermined time control over the closing

of a plurality of electric circuits, or for permitting a single circuit to remain closed for a predetermined length of time.

To these and other ends, the invention consists in the construction and arrangement of parts that will appear clearly from the following description when read in conjunction with the accompanying drawing, the novel features being pointed out in the claims following the specification.

In the drawing:

Fig. 1 is a sectional view of a structure built in accordance with a preferred embodiment of the invention, showing the solenoid plunger and circuit controlling member in initial position, prior to closing the solenoid controlling circuit;

Fig. 2 is a similar view, illustrating the position of the solenoid plunger and circuit controlling member in the position occupied after the plunger has been actuated to its lowermost position and started its return movement, the circuit controlling member being shown in position to close the first circuit of the series, the lowermost position of the solenoid plunger and circuit controlling member being shown in dotted lines;

Fig. 3 is a horizontal sectional view on the line 3—3 of Fig. 2;

Fig. 4 is a horizontal sectional view on the line 4—4 of Fig. 2;

Fig. 5 is a horizontal sectional view on the line 5—5 of Fig. 2, and

Fig. 6 is a diagrammatic view of the circuits to the chime striker mechanisms, and the controlling circuit therefor.

The invention is applicable in various relationships wherever it is essential to provide a low cost structure occupying a small space with parts compactly arranged, particularly in such applications as small chime signals, although it has many other possible uses wherever one or more electric circuits are to be governed by a timing mechanism, and the embodiment illustrated shows the invention as applied to a chime signal circuit including three individual chime bars and electric striker mechanisms, adapted to be successively operated at predetermined intervals, when the controlling circuit is closed.

Referring more particularly to the drawing, in which like reference numerals refer to the same parts throughout the several views, and to Fig. 6, 1 and 2 designate conductors leading from a suitable transformer in a power circuit, the conductor 1 being grounded, and conductor 2 including a push button or other switch 3, by which the controlling circuit is manually closed. The

push button switch 3 is in a conductor that leads to a terminal 4 of the timing mechanism to be described presently, while conductor 5 leads from conductor 2 to the solenoids 6, 7 and 8 which include plungers and strikers arranged to sound the chime bars 9, 10 and 11 respectively, as usual in this class of apparatus.

The solenoids 6, 7 and 8 are connected to terminals 12, 13 and 14 of the timing mechanism, the last mentioned solenoid 8 being also connected to terminal 15 for a purpose that will appear presently. With this arrangement, when the push button switch is closed, the timing mechanism causes the solenoids just referred to to be operated successively at predetermined intervals, the solenoid 8 being operated twice, both at the beginning and end of the cycle, causing the chime bars to be struck correspondingly. The general arrangement of mechanism thus far described is of conventional character and forms no part of the present invention, except as to the timing mechanism, which will now be set forth in detail.

Referring to Figs. 1 and 2, the structure includes a housing or shell that is preferably cylindrical and drawn from a single piece of metal so as to avoid a seam or joint, and as shown includes an enlarged body portion 17 and a reduced lower end portion or well 18, although it is not essential that the lower end portion be of reduced cross-section.

Between the reduced lower end portion 18 and the body portion 17 is provided a ledge 19 upon which rests a metal supporting plate 20, the edge of which engages the housing, and which is provided with openings 21 to permit passage of oil therethrough. Supported on the plate 20 is a solenoid coil 22 positioned between insulating end plates 23, and 24 is a metal tube that extends through the solenoid and end plate 23. The tube 24 also extends through a central opening in the supporting plate 20, and a corresponding opening in a metal retaining plate 25 which has peripheral openings 26, and resting upon the outer end plate 23 of the solenoid. The retaining plate 25 is driven or pressed in the housing and holds the solenoid tightly in place without the necessity of brackets, rivets, welds, screws, or other fastening means. The plates 20 and 23 both engage the housing at their edges and the tube 24 at the center, and thus complete the magnetic circuit which extends through the tube, plates, and housing.

The bottom edge of tube 24, within which the solenoid plunger is movable, engages a ball 27 that is seated in a conical spring 28, the latter being supported in the bottom of the housing as shown and acting to hold the ball 27 normally against the bottom of the tube 24 for a purpose that will appear presently.

The solenoid plunger movable within the tube 24 is designated at 29, and carries a circuit controlling member or arm 31, which operates to close successively the several solenoid circuits to the striker mechanisms already mentioned, when the solenoid plunger 29 is operated, the latter being grounded through the tube 24 and the housing. The circuit controlling member or arm 31 wipes over contacts or conductors 32, 33, 34 and 35, in the order mentioned during its upward movement, said contacts being connected with and corresponding to the terminals 15, 12, 13 and 14 already referred to.

To accomplish this, there is provided a closure or head 36 of any suitable insulating material

that carries the terminals and is pressed tightly into the housing to afford a liquid-tight seal preventing the leakage of oil.

The closure 36 has a depending preferably integral supporting post 37. The terminals 12, 13, 14 and 15 are embedded in said closure or insulating head 36, extending through the same, and at their lower ends have attached thereto by soldering or in any suitable manner the conductors which extend thence around the insulating supporting post 37 in suitable annular grooves 38, and thence through transverse openings 39 in the post 37. The end of each conductor is then soldered at 40 and thus provides the aforementioned contacts 32, 33, 34 and 35 on the post 37. The conductors from the several solenoids 6, 7 and 8 aforementioned are soldered or otherwise connected to the terminals 12, 13, 14 and 15 in any suitable fashion, while terminals 4, to which the conductor 2 is secured, extends through the insulating closure or head 36, and has connected to it a conductor 42 that leads from its lower end to the solenoid 22.

43 is a coil spring surrounding the plunger 29 above the retaining plate 25 which is fixed in the housing, the lower end of said spring being bent downwardly and engaging one of the openings 26 in said plate 25, while its upper end is bent around the arm 31. The spring thus acts to return the plunger upwardly to its initial position when released and also to turn the plunger and retain the circuit controlling member or arm 31 against the supporting post 37 during the endwise movement of the plunger after it has been drawn downwardly by the closing of the circuit to coil 22 through manual operation of the push button 3, and when the latter is released.

44 The housing 17 is filled with oil or other suitable liquid up to the level indicated, and as the plunger 29 is drawn quickly downwardly when solenoid 22 is energized, it forces the oil from tube 24 downwardly and outwardly past ball 27. Upon upward movement of the plunger 29, the spring 28 returns the ball 27 into engagement with the lower end of the tube 24, and prevents fast movement of the oil into the tube, but permits it to move in slowly around the ball 27, the oil also passing slowly into the top of the tube 24 and downwardly around the plunger 29. The openings 26 in the retaining plate 25, and openings 21 in the lower plate 20, permit free movement of the oil from around the coil 22 downwardly into the well 18, the action of the oil retarding upward movement of the plunger 29, causing it to move slowly and thus effecting a suitable time interval between the closing of the several individual striker circuits. The action of the spring in returning the plunger upwardly is greatest at the beginning of the movement when its compression is greatest, and to compensate for this, the distance between the contacts may be decreased upwardly so as to attain a substantially uniform interval between the successive circuit closing operations.

70 The operation of the device briefly described is as follows: Assuming the plunger to be in its uppermost position as shown in Fig. 1, by operating the push button 3, the circuit to solenoid 22 is closed, causing plunger 29 to be drawn quickly downwardly to its lowest point with the circuit controlling member or arm 31 in the dotted line position indicated in Fig. 2, and somewhat beneath the lowest contact 32. The plunger will remain in this position as long as the switch 3

is closed, and upon release of the latter, the spring 43, which has been compressed, acts to move the plunger upwardly, such upward movement being suitably retarded by the action of valve 27 that prevents fast movement of the oil into the tube 24 behind the plunger.

In this fashion, the circuit controlling member 31 moves slowly upwardly over the contacts 32, 33, 34 and 35, and thus successively closing the circuits to solenoids 8, 7, 6 and 8, causing the chime bars to be struck correspondingly. While the arm 31 passes these contacts on its downward movement, it is only an instantaneous engagement, the plunger traveling downwardly at such a speed under the impulse of the solenoid that it does not maintain engagement with the contacts sufficiently long to affect the solenoids in the striker mechanism circuits.

While the invention has been described with reference to the structural details herein disclosed, it is not confined to this particular embodiment, and the application is intended to cover any further changes or modifications that may come within the purposes of the invention and the scope of the following claims.

I claim:

1. An electric timing mechanism including a housing of conducting material, a solenoid arranged in the housing, a solenoid plunger movable in the solenoid, spring means for returning the plunger to initial position when released, fluid controlled means acting to retard the return movement of the plunger, a circuit controlling member carried by the plunger, a closure of insulating material, a series of terminals carried by said closure, one of said terminals being connected with the aforementioned solenoid, a support of insulating material carried by said closure and extending inside the housing parallel to said plunger, and a series of contacts arranged in spaced relation endwise of said support to be engaged by said circuit controlling member as the plunger moves endwise and connected with the aforesaid terminals on the closure.

2. An electric timing mechanism including a housing of conducting material, a solenoid held frictionally in the housing, a solenoid plunger movable in the solenoid, spring means for returning the plunger to initial position when released, fluid controlled means acting to retard the return movement of the plunger, a circuit controlling member carried by the plunger, a liquid-tight closure of insulating material, a series of terminals carried by said closure, one of said terminals being connected with the aforementioned solenoid, a support of insulating material carried by said closure and extending inside the housing parallel to said plunger, and a series of contacts on said support disposed for engagement by said circuit controlling member on the plunger and connected to said terminals.

3. An electric timing mechanism including an integral housing closed at one end, a solenoid in the housing, supporting and retaining plates engaging the solenoid and housing and acting to hold the solenoid frictionally in the housing, a solenoid plunger movable in the solenoid, spring means for returning the plunger to initial position when released, fluid controlled means acting to retard the return movement of the plunger, a circuit controlling member carried by the plunger, a liquid-tight closure of insulating material, a series of terminals carried by said closure, one of said terminals being connected with the aforementioned solenoid, a support of insulating mate-

rial carried by said closure and extending inside the housing parallel to said plunger, and a series of contacts on said support disposed for engagement by said circuit controlling member as the plunger moves endwise and connected to said terminals on the closure.

4. An electric timing mechanism including a housing closed at one end, a solenoid in the housing, a solenoid plunger movable in the solenoid, a circuit controlling member carried by said plunger, spring means acting to return the plunger to initial position when released, liquid controlled means acting to retard the return movement of the plunger, a closure of insulating material at the opposite end of the housing, a series of terminals carried by said closure, a support of insulating material carried by said closure and extending inside the housing parallel to the plunger, and a series of contacts arranged in spaced relation endwise of said support to be engaged by said circuit controlling member as the plunger moves endwise and connected with the aforementioned terminals on the closure.

5. An electric timing mechanism including an integral housing closed at one end, a solenoid held frictionally in the housing, the housing acting as one leg of a magnetic circuit for the solenoid, a solenoid plunger movable in the solenoid, a circuit controlling member carried by said plunger, spring means acting to return the plunger to initial position when released, liquid controlled means acting to retard the return movement of the plunger, a liquid-tight closure of insulating material at the opposite end of the housing, a series of terminals carried by said closure, a supporting post of insulating material carried by said closure and extending inside the housing parallel to the plunger, and a series of contacts on said post in position to be engaged by said circuit controlling member as the plunger moves endwise and connected with the aforementioned terminals, said spring means acting to turn the plunger and hold the circuit controlling member against the post during endwise movement of the plunger.

6. An electric timing mechanism including a housing having a closed lower end of reduced cross-section affording a ledge at the top of said reduced portion, a supporting plate removably positioned on said ledge, a solenoid located within the housing and mounted on said supporting plate, a retaining plate held within the housing and engaging the upper end of said solenoid to hold the latter against said supporting plate, a solenoid plunger located entirely within the housing and movable in the solenoid, a tube in which said plunger travels, said tube extending through central openings in the supporting and retaining plates, a circuit controlling member carried by the plunger, spring means acting to move the plunger upwardly to initial position when released, a closure of insulating material at the upper end of the housing, a series of terminals carried by said closure, a support of insulating material carried by said closure and extending inside the housing parallel to the plunger, a series of contacts arranged in spaced relation endwise of said support to be engaged by said circuit controlling member as the plunger moves endwise and connected with the aforementioned terminals on the closure, and liquid controlled means including a body of liquid covering said solenoid and acting to retard the upward movement of the plunger, said supporting and retaining plates having peripheral openings permitting passage of said liquid therethrough.

7. An electric timing mechanism including a housing having a closed lower end of reduced cross-section affording a ledge at the top of said reduced portion, a supporting plate removably positioned on said ledge, a solenoid located within the housing and mounted on said supporting plate, a retaining plate held within the housing and engaging the upper end of said solenoid to hold the latter against said supporting plate, a solenoid plunger located entirely within the housing and movable in the solenoid, a tube in which said plunger travels, said tube extending through central openings in the supporting and retaining plates, a circuit controlling member carried by the plunger, spring means acting to move the plunger upwardly to initial position when released, a closure of insulating material at the upper end of the housing, a series of terminals carried by said closure, a support of insulating material carried by said closure and extending inside the housing parallel to the plunger, a series of contacts arranged in spaced relation endwise of said support to be engaged by said circuit controlling member as the plunger moves endwise and connected with the aforementioned terminals on the closure, a body of liquid surrounding the solenoid and plunger, said supporting and retaining plates having peripheral openings permitting passage of the liquid therethrough, and a valve member positioned in said reduced lower end of the housing and held yieldably against the lower end of said tube and acting to permit quick movement of the liquid downwardly from the tube when the plunger travels downwardly and to retard movement of liquid into the tube during the upward travel of the plunger.

8. An electric timing mechanism including a

housing having a closed lower end of reduced cross-section affording a ledge at the top of said reduced portion, a supporting plate removably positioned on said ledge, a solenoid located within the housing and mounted on said supporting plate, a retaining plate held within the housing and engaging the upper end of said solenoid to hold the latter against said supporting plate, a solenoid plunger located entirely within the housing and movable in the solenoid, a tube in which said plunger travels, said tube extending through central openings in the supporting and retaining plates, a circuit controlling member carried by the plunger, spring means acting to move the plunger upwardly to initial position when released, a closure of insulating material at the upper end of the housing, a series of terminals carried by said closure, a support of insulating material carried by said closure and extending inside the housing parallel to the plunger, a series of contacts arranged in spaced relation endwise of said support to be engaged by said circuit controlling member as the plunger moves endwise and connected with the aforementioned terminals on the closure, a body of liquid surrounding the solenoid and plunger, the supporting and retaining plates having peripheral openings to permit passage of the liquid therethrough, a spring seated at the bottom of the housing in said reduced portion, and a ball valve supported by said spring and held yieldably thereby against the lower end of said tube, said yieldable ball valve acting to permit quick movement of the liquid from the tube when the plunger travels downwardly and to retard movement of liquid into the tube when the plunger travels upwardly.

LLOYD RITTENHOUSE.
